HOLDING CLIP

John K. Reed, Charlevoix, Mich.

Application July 2, 1948, Serial No. 147,347

Term of patent 3½ years

(Cl. D17—3)

To all whom it may concern:

Be it known that I, John K. Reed, a citizen of the United States, residing at Charlevoix, in the county of Charlevoix and State of Michigan, have invented a new, original, and ornamental Design for a Holding Clip, of which the following is a specification, reference being had to the accompanying drawing, forming part thereof.

Fig. 1 is a perspective view of a holding clip showing my new design.

Fig. 2 is a side elevation of the same, and
Fig. 3 is a rear elevational view thereof.

I claim:

The ornamental design for a holding clip, substantially as shown.

JOHN K. REED.
